CLAIM

The ornamental design for an electric grinder, as shown and described.

DESCRIPTION

FIG. 1 is a perspective view of an electric grinder showing the new design in a closed state.

FIG. 2 is a perspective view of the electric grinder of FIG. 1 in an open state.

FIG. 3 is a front view of the electric grinder of FIG. 1.

FIG. 4 is a rear view of the electric grinder of FIG. 1.

FIG. 5 is a side view of the electric grinder of FIG. 1.

FIG. 6 is an opposite side view of the electric grinder of FIG. 5.

FIG. 7 is a top view of the electric grinder of FIG. 1.

FIG. 8 is a bottom view of the electric grinder of FIG. 1.

FIG. 9 is an enlarged front view, taken from within portion ‘9’ on FIG. 1; and,

FIG. 10 is an enlarged front view, taken from within portion ‘10’ on FIG. 3.

The evenly broken lines represent parts of the article, forming no part of the claimed design. The dot-dash broken lines represent the designation of the enlargement views and form no part of the claimed design.

1 Claim, 10 Drawing Sheets
